SAFETY MEANS FOR RECEPTACLES

Raymond Francis Hatala and Arthur Kimber,
Streator, Ill., assignors to Anthony Company,
Streator, Ill., a corporation of Illinois

Application June 21, 1944, Serial No. 541,452

7 Claims. (Cl. 220—89)

1

This invention relates to a fire protection means. In the particular form here shown it is applied to a washer in which the washing fluid may be inflammable and in which it is desirable to provide automatic means for closing a door or a cover should fire occur, and one of the objects of the invention is, therefore, to produce such an automatic closure operating means for use in connection with a washer. The invention is not, however, limited to this use and may be embodied in a structure for any other purpose where it is desirable to provide an automatic control or operating means for a closure.

Another object is to provide in connection with such a means a heat responsive part which, when the temperature rises above a predetermined limit, will operate automatically to accomplish closing.

Other objects will appear from time to time throughout the specification and claims.

The invention is illustrated more or less diagrammatically in the accompanying drawings, wherein:

Figure 1 is a side elevation of one form of the device in position on a washer, parts of which are omitted, broken away and in section;

Figure 2 is an elevation of a portion of a washer with the closing, controlling means shown in elevation;

Figure 3 is a side elevation on an enlarged scale of the controlling means shown in Figures 1 and 2; and

Figure 4 is a plan view on a further enlarged scale of the heat-responsive member.

Like parts are indicated by like characters throughout the specification and the drawings.

In the particular form here shown, the device comprises a closure 1. This closure is hinged, as at 2, to a base member 3. As shown herewith, the base member is part of a washer casing or housing, but the closure might be mounted on any other base or support. A stop 4 may be provided to limit the opening movement of the closure.

The closure operating and controlling means includes a member 5 which is more or less in the form of a bell crank and is pivoted, as at 6, upon a support 7 which is secured to the closure 1. The member 5 is pivotally or movably joined, as at 8, to a similar bell crank member 9. One arm of this member may, in one position of adjustment, rest upon an abutment or support 10 which, in the form here shown, is fixed on the base member 3. The bell crank members 5 and 9 are provided with hook or engaging parts 11 and 12.

2

A heat-responsive link 13 is normally mounted between the bell crank members and engaged upon the hook or attaching means 11 and 12.

As shown particularly in Figure 4, the link 13 is provided with perforations 14 which may engage the members 11 and 12. Obviously, instead of perforations, notches, projections or enlargements might be used, so long as some shape or means is provided whereby the link 13 may be engaged with or secured to the free ends of the bell cranks 5 and 9. If desired, the link may be cut away, as at 15, to reduce its thickness. The link is preferably made of some readily inflammable material, such as Celluloid or other cellulose material. It may, of course, be made of metal or other material having a low melting point. Experience has shown that a cellulose or Celluloid link which responds at a lower temperature than will most readily fusible metals or other materials is preferable.

Since it is important to have the closure of this invention operate promptly at the very beginning of excessive temperatures, it is desirable to have the heat-responsive link formed of a material which will not merely respond to heat, but which is combustible and hence, once the heating effect has commenced, will carry on until destruction. For this purpose an inflammable member is useful, and the cellulose link suggested is sufficiently inflammable, once it has been ignited, to continue burning until it has been destroyed.

While the closure may under some conditions be arranged to close by gravity alone, it is often desirable to accelerate the closing and to make it more certain of occurrence. For this purpose spring-loaded means are desirable. In the particular form here shown, these include a bolt 16 which is secured at one end either to the member 12 or to some other part fixed in relation to the free end of the bell crank 9. A stop 17 which may include a lock nut and a washer is fixed on the opposite end of the bolt 16, and a spring 18 is positioned about the bolt and bears at one end against the stop 17 and at its other end upon an abutment or stop 19 which is part of or supported from the base member 3. By this construction the spring is under compression and will, when free to do so, accelerate the closing of the closure.

Although we have shown an operative form of our invention, it will be recognized that many changes in the form, shape and arrangement of parts can be made without departing from the spirit of the invention, and our showing is therefore to be taken as, in a sense, diagrammatic.

The exact shape of the bell crank members 5 and 9 is not essential to the invention and, in fact, other members might be used so long as they serve to engage the fusible inflammable or other heat responsive link and so long as they serve to hold the closure in the raised position until destruction of the link 13. The invention is therefore not limited to the particular linkage or lever system shown.

The use and operation of this invention are as follows:

Under normal conditions the closure is intended to be held open and it is so shown in Figures 1 and 2. As thus shown, a link 13 is fixed between the free ends of the bell cranks 5 and 9 and prevents relative pivotal or other movement of these bell cranks. The lower end of the bell crank 9 is seated upon or rested upon the abutment 10. With the parts in this position, the spring 18 is under compression and tends to close the closure. However, the closing movement is resisted by the two bell cranks which act as a single solid member so long as the link is intact. The two bell cranks and the link, thus acting as a solid member, hold the closure open.

When temperatures above a predetermined point occur in or near the washer, the link 13 is fused or burned. As above mentioned, it may be made of combustible material and will then burn rapidly and destruction will be complete. Whatever the material of the link, once it has been destroyed it no longer prevents relative movement of the bell cranks 5 and 9. The spring 18 is then free to pull the crank 9 downwardly and this crank rotates about the abutment 10 and thus pulls the bell crank 9 to the left from the position shown in Figure 1, thus overbalancing the entire closure and causing it to move at once to the closed position.

After the fire or other excessive heat in or near the washer is removed, the closure is raised manually, a new link is put in place between the members 5 and 9, and the parts are restored to the position shown in Figures 1 and 2. The means of attaching the link to the levers 5 and 9 is preferably such that the link may be easily put in place or removed. At the end of work or when the washer is to be put out of operation, it is generally desirable to lower the closure and this can be done by merely removing the link and permitting the closure to move to the closed position. For this purpose ordinarily the operator will pull up on the bolt 16 to reduce the tension on the link 13. He can then remove the link and lower the closure to the closed position. Similarly, when the washer is to be put into use again, the closure is raised and a new link is inserted in the manner described above for the operation which occurs after the link has been destroyed by excessive temperatures.

We claim:

1. In combination, a base member, a closure mounted thereon for relative movement therewith, and means for controlling said movement comprising two members, one of said members hinged to said closure, the said members being hinged together, an abutment fixed on said base member, one of said members being adapted to rest upon said abutment, and a heat responsive link positioned between and engaging each of said members, and when in position holding them against relative movement, the two members and said link, when so assembled, comprising an assembly effective to hold the closure against movement, the said members being freed for relative

5 hinge movement upon the destruction of said heat responsive link, and means biased to move one of said members and thereby to tilt the other and to close the closure.

2. In combination, a base member, a closure mounted thereon for relative movement therewith, and means for controlling said movement comprising two bell crank members, one of said members hinged to said closure, the two bell crank members being hinged together, an abutment fixed on said base member, one of said bell crank members being adapted to rest upon said abutment, and a heat responsive link positioned between and engaging each of said bell crank members, and when in position holding them against relative movement, the two bell crank members and said link, when so assembled, comprising an assembly effective to hold the closure against movement, the bell crank members being freed for relative movement upon the destruction of said heat responsive member, and means biased to move one of said bell crank members and thereby to tilt the other and to close the closure.

3. In combination, a base member, a closure mounted thereon for relative movement therewith, and means for controlling said movement comprising two bell crank members, one of said crank members hinged at one end to said closure, the two bell crank members being hinged together, an abutment fixed on said base member, one of said bell crank members being adapted to rest upon said abutment, and a heat responsive member positioned between and engaging each of said bell crank members, and when in position adapted to hold them against relative movement, the two bell crank members and said link, when so assembled, comprising an assembly effective to hold the closure against movement, the bell crank members being freed for relative movement upon the destruction of said heat responsive member, and means biased to move one of said bell crank members and thereby to tilt the other and to close the closure.

4. In combination, a base member, a closure mounted thereon for relative movement therewith, and means for controlling said movement comprising two members, one of said members hinged to said closure, the two members being hinged together, an abutment, the other of said members being adapted to rest upon said abutment fixed on said base member, and a heat responsive member positioned between and engaging each of said members, and when in position adapted to hold them against relative movement, the two members and said link, when so assembled, comprising an assembly effective to hold the closure against movement, the members being freed for relative movement upon the destruction of said heat responsive member, and spring loaded means biased to move one of said members and thereby to tilt the other and to close the closure.

5. In combination, a base member, a closure mounted thereon for relative movement therewith, and means for controlling said movement comprising two parts, one of said parts hinged to said closure, the two parts being hinged together, an abutment fixed on said base member, the other of said parts being adapted to rest upon said abutment, and an inflammable link positioned between and engaging each of said parts, and when in position adapted to hold them against relative movement, the two parts and said link, when so assembled, comprising an assembly effective to hold the closure against movement, the parts be-

ing freed for relative movement upon the destruction of said inflammable member, and means biased to move one of said parts and thereby to move the other and to close the closure.

6. In combination, a base, a closure pivotally mounted thereon for relative movement therewith, and means for holding said closure in the open position, said means comprising a pair of members pivoted together, and one of said members pivoted on said closure at a point remote from the pivotal connection between the base and closure, an abutment fixed on said base, the other pivoted member adapted to contact said abutment at a point spaced from that at which it is pivoted to said other member, a rigid inflammable part connected to each of said members away from the point at which they are pivoted together and holding them against relative movement, said two members and said part forming a rigid means holding said closure raised, and spring loaded means tending at all times to close said closure, said members forming, with the inflammable part, a stop to prevent closing while the inflammable part is intact, the said members being freed for relative movement upon the destruction of said part, the spring loaded means thereupon being effective to tilt one of said parts, which in turn moves the other of said parts and closes the closure.

7. In combination, a base, a closure mounted

thereon for relative movement therewith, spring loaded means tending at all times to move said closure to close it against said base, and means for preventing said movement, said means including a pair of bell crank members pivoted together, one of said members being pivoted also upon said closure, the other being seated upon said base, and an inflammable link holding said bell cranks against relative movement while it is intact, said spring loaded means being connected to the bell crank which is seated upon said base at a point away from the point of contact of said bell crank with said base, and adapted when said link has been destroyed to cause said bell crank to pivot about its point of contact with said base and thereby to move said other bell crank and to carry with it said closure.
